UNITED STATES PATENT OFFICE.

JAMES YOUNG, OF WOONSOCKET, RHODE ISLAND.

TURNING-MACHINE.

No. 884,451.

Specification of Letters Patent. Patented April 14, 1908.

Application filed October 14, 1907. Serial No. 397,279.

To all whom it may concern:

Be it known that I, JAMES YOUNG, citizen of the United States, residing at Woonsocket, in the county of Providence and State of Rhode Island, have invented new and useful Improvements in Turning-Machines, of which the following is a specification.

My invention pertains to wood turning; 10 and it contemplates the provision of a machine designed more especially for turning wood bobbins and analogous articles, and constructed with a view of automatically engaging a properly placed blank, expeditiously 15 reducing the same to the shape desired, and automatically releasing the turned article so as to permit of the ready removal thereof. In other words my invention seeks the provision of a wood turning machine which by 20 reason of the automatic action of its parts leaves nothing for the operator to do but to place the blanks between the centers and remove the articles from the machine subsequent to the turning operation.

25 The invention also contemplates the provision of a wood turning machine embodying simple and efficient means through the medium of which the working parts may be easily and expeditiously stopped at any time 30 to prevent injury thereto in case of accident.

Other advantageous features of the invention will be fully understood from the following description and claims when the same are read in connection with the drawings, accompanying and forming part of this specification, in which:

Figure 1 is a plan view of the machine constituting the best embodiment of my invention known to me, Fig. 2, a front elevation; 40 Fig. 3, a rear elevation; Fig. 4, a detail, longitudinal, vertical section with the parts in the positions they occupy when the centers are in engagement with a blank or piece of stock; Fig. 5, a similar view with the parts 45 in the positions they assume after a turned article has been "knocked off" the centers; Fig. 6, a transverse section, taken on the line 6—6, of Fig. 1; Fig. 7, an enlarged detail showing certain cams and the clutch of the 50 machine; Fig. 8, an enlarged detail illustrative of the headstock center and the knocking off mechanism; Fig. 9, a transverse section taken in the plane indicated by the line 9—9 of Fig. 8; Fig. 10, a detail, 55 horizontal section, taken in the plane indicated by the line 10—10 of Fig. 9.

Similar letters and numerals designate corresponding parts in all of the views of the drawings, referring to which:

C is the bed of my novel machine; A, a frame fixed to and rising from the bed; B, a frame rising from the bed and adjustably fixed thereto; M, a longitudinally-disposed drive shaft, journaled in suitable bearings at the rear of the bed C and provided at its inner 60 end with a pinion *j* and at its outer end with a stepped pulley T designed to be connected through a belt (not shown) with an ordinary countershaft; O, a transverse shaft journaled in suitable bearings on the bed and 65 provided with a spur gear *i* and cams *s* *s'* *u* and *p*; N, a shaft journaled in bearings on the bed; *k*, a miter gear fixed on shaft N and intermeshed with the pinion *j* of shaft M and carrying a clutch member 107 at its inner 70 side; V, a sleeve loosely arranged on and movable in the direction of the length of the shaft N and having a gear 110 intermeshed with the gear *i* of shaft O and also having a clutch member 108 at its outer end 75 complementary and opposed to the clutch member 107 of miter gear *k*; and *W'*, a hand lever, fulcrumed at *w'* on the bed C and having a bifurcated lower end disposed in a circumferential groove 109 of the sleeve V. 80

Certain of the working parts of my novel machine derive motion from the shaft O, as will be presently described, and motion is transmitted from the continuously rotating shaft M to the shaft O through the gear *j*, the 90 gear *K*, the sleeve V, its gear 110 and the gear *i* so long as the clutch member 108 is in engagement with the clutch member 107. When, however, the sleeve V is moved through the lever *W'* to carry the clutch 95 member 108 inward away from the member 107, the shaft O and the parts operated thereby will stop. The lever *W'* may be quickly and conveniently operated for the purpose stated and in that way the parts operated from the shaft O may be stopped at any stage in the operation to prevent damage thereto in the event of an accident. Said lever *W'* may also be quickly and easily operated to engage the clutch member 108 with 100 the clutch member 107, and so long as the said members are in engagement the shaft O will be rotated from the continuously rotating shaft M.

D is a live head stock spindle, journaled in 110 suitable bearings in the frame B and provided with a center *W'* and a stepped pulley

E; the latter being designed to be connected with a countershaft (not shown).

U is a longitudinally-disposed bar connected to the inner end of the frame B and 5 having a reduced forward portion and a beveled or inclined shoulder 104 on its lower edge immediately in rear of the said reduced portion.

D' is a longitudinally-movable tail stock 10 spindle arranged in the frame A and having a center W at its inner end; v', a V-shaped support for blanks, arranged below the inner portion of the spindle D' and fixedly connected through a rod Q with the inner end of 15 the fixed frame A; Y, a longitudinally-disposed, horizontal rod fixedly connected through a hanger x' with the spindle D'; x, an upright fixed, preferably in an adjustable manner on the rod Y and having means such 20 as an eye x³ at its upper end loosely receiving the spindle D; v, a vertically-movable, V-shaped support for blanks or pieces of stock, loosely connected with the upright x through the medium of a screw 100 (Figs. 8—10) and 25 having a lateral arm 101; 102, a lateral arm on the upright x, from which rises a post 103, loosely arranged in the lower end of the stock support v; and n'', a coiled spring surrounding the post 103 and interposed between the arm 102 of upright x and the lower 30 end of the support v and having for its office to yieldingly maintain the said support v in the raised position shown in Fig. 5.

In the operation of my novel machine, the 35 square or rough turned blanks or pieces of stock, which usually have longitudinal-central bores, are placed one by one in and removed from the V-shaped portions of the supports v and v' by the operator, and they 40 are each "knocked on" and "knocked off" the center as follows: When the head-stock spindle D' is moved inward by means presently described, the end of a blank or piece of stock, previously placed on the center and 45 in the supports v' and v, will be forced on the center W' of the live tail-stock spindle D so as to turn therewith. On the said inward movement of the spindle D', the blank or piece of stock will be moved thereby off the 50 support v', which is fixed with respect to the fixed frame A and at the same time the rod Y, the upright x and the support v will be moved in the same direction as the spindle D', whereupon, by reason of the arm 101 of 55 the support v moving over the shoulder 104 and against the lower edge of the wide portion of the bar U, the support v will be drawn downward and away from the blank or piece of stock, leaving the latter free to turn on 60 the centers W and W'. This operation of "knocking on" takes place before the blanks or piece of stock is turned by the means hereinafter described to the shape desired, and after the turning operation, the article is 65 "knocked off" as follows: On outward move-

ment of the spindle D', effected by means presently described, and the synchronous movement of the rod Y and the upright x, said upright x will force the turned article off the center W' and the article will drop on 70 the supports v' and v, ready to be taken away by the hand of the operator. Meanwhile, the arm 101 of the support v will have moved to a position below the comparatively narrow part of the bar U, and the spring n'' 75 will have raised the support v to the position shown in Fig. 5, ready to receive a fresh blank or piece of stock from the hand of the operator. At this point it should be noted that during the operation of the machine, all 80 the operator has to do is to place the blanks or pieces of stock one by one on the supports v and v' and remove the turned articles from said supports, and consequently the operator is free to use one hand to place blanks in position and the other hand to remove turned articles. This will be appreciated as an important advantage when the rapidity with 85 which the turned articles are produced is considered.

The described inward, endwise movement of the spindle D' is effected by the cam s on the shaft O engaging an anti-friction roller z on a lever P fulcrumed on the bed C and connected to the said spindle D', Fig. 5, and the 95 following outward, endwise movement of the spindle D' is caused by the cam s' on shaft O operating against anti-friction roller z' on a lever P' which is also fulcrumed on the bed C and connected to the said spindle D'.

H is a frame arranged transversely on and fixedly connected to the bed C. G G, Figs. 1 and 6, are parallel, longitudinal rails mounted on said frame H, and F is a tool carriage, movable on said rails in the direction of the length of the machine. The said carriage F is moved toward the right by the mechanism shown at the right of Fig. 2 and toward the left by the mechanism illustrated 100 at the left of Fig. 2. The first mentioned mechanism comprises a rod n, pivotally connected at m to the carriage F and preferably adjustable as to length, a lever K fulcrumed at 117 on an adjustable bracket w' connected 115 with bed C and having its long arm connected at f to the outer end of the rod n and also having a preferably adjustable, anti-friction roller r on its short arm 118, and the before described cam p on the shaft O, which cam is 120 arranged to engage said roller r. Incident to rotation of the said shaft O in the direction indicated by arrow, the cam p co-operating with lever K will obviously move the carriage F in the direction indicated by the arrow on said carriage, and then move out of engagement with the lever K, leaving the latter free to swing in the opposite direction. The second mentioned mechanism for moving the carriage F comprises a cable 120 at 125 130

tached to the carriage and passed over a sheave p' on the bed C, and a spiral spring C³ connected to the cable 120 and designed to be fastened to the floor or at any other suitable point. The latter mechanism serves to draw the carriage F in the direction opposite to the arrow on the carriage, Fig. 2, after cam p passes out of engagement with anti-friction roller r , and the spring C³ in said 10 mechanism is preferably a slack coiled spring which is advantageous since it loses power as it approaches its normal position of rest, thus drawing the carriage F to the starting point with much less force than if a weight were 15 employed for the purpose, for the weight would gain speed in proportion to the length of its drop.

The movement of the carriage F toward the left in Fig. 2 is limited by a stop b in the 20 form of a plunger mounted in a guide b³ and backed by a spring, an air cushion or other suitable means; the said guide b³ being preferably carried by a bracket d, adjustably connected to bed C.

25 Mounted upon and suitably connected to the carriage F is a tool post or supporting frame S in which is a shaft 111 on which tool holders t are pivotally mounted. Tools 9 and 10, Figs. 1 and 6, which are shown as 30 roughing tools but which are not necessarily of that type, are arranged in the holders t upon bars 112 and are adjustably fixed in the holders and upon the bars 112 by binding screws 1 and 2 bearing in the tops of the 35 holders and against the tools. Posts J, Fig. 6, arranged beneath the inner ends of the bars 112 and connected to the frame S, serve to limit downward movement of the cutting ends of the tools 9 and 10, and the said bars 40 112 are normally held against the posts J by spring strips 113, Figs. 2 and 6, which are connected to the frame S and bear upward against the outer portions of the bars 112 and thereby yieldingly hold the cutting ends of 45 the tools to their work.

J' is a longitudinal guide arranged at the front of the machine and carried by brackets I' connected to the undersides of the rails G. The said guide co-operates with rollers h' on the outer ends of the tool supporting bars 112 to guide by its irregular shape the tools 9 and 10 when the carriage F is moved in the direction of the arrow thereon in Fig. 2, and in that way enable the said tools to 55 shape the work thereby relieving the finishing tool of heavy cutting.

The transversely arranged, fixed frame H is provided with undercut ways or grooves 121, Figs. 2, 3 and 4, and on said frame is arranged a carriage L, movable transversely of the machine and having tongues 122 disposed under said ways 121. At its outer end the carriage L has a bracket 7 in which bears a screw 123, arranged to engage the rear end 60 of the frame H with a view of limiting the in-

ward or forward movement of said carriage and the tool, presently described, carried thereby. Arranged on the carriage L and secured thereto by bolts bearing in flanges 124^a and engaging one end of the carriage, Fig. 3, is a frame 124 having a longitudinal, vertical portion 125 in which is a longitudinal, horizontal slot 126. The said portion 125 is for the connection of tool holders 127 and 128, preferably of general right-angle form; the connection being affected through bolts secured in the said slot 126, Figs. 3 and 6. The outer or rear horizontal portion of the tool holder 127 is supported by bolts 5 and 6 connected to the holder and bearing on frame 124, and consequently the finishing tool 11, connected to the holder 127 through bolts 129 or other suitable means, may be conveniently adjusted and adjustably fixed with respect to the frame 124 and the carriage L. 70 75 80 85

The carriage L is translated or moved inward and outward on the frame H by the following means: On the underside of the said carriage L is a rack R', Figs. 4 and 6, with which is intermeshed a sector gear 12, 90 fixed on a longitudinally-disposed shaft 13, journaled in bearings carried by frame H, and the said shaft 13 is provided with a crank arm 15, connected through a link 14 with a lever K' which is fulcrumed loosely on the transverse shaft N and is provided with a weight w'' and an upwardly reaching portion w³, bearing an anti-friction roller z''. This latter is arranged to be engaged by the 95 before mentioned cam u on the transverse shaft o, and the operation of this portion of the machine is as follows: During rotation of the shaft O, the cam u acting against roller z'' raises the weighted end of lever K' and depresses the opposite end thereof, and causes the latter end, through the link 14 and crank arm 15, to rock the shaft 13 and sector gear 12 in the direction of the arrow in Fig. 6, and through said sector gear and rack R' 100 move the carriage L inward so as to carry the finishing tool or tools into engagement with the blank or piece of stock on the centers. When the cam u moves out of engagement with the roller z'' of lever K', the 105 weight w'' rocks the lever in the direction opposite to that just mentioned and through the medium of the mechanism described moves the carriage L and the tool or tools thereon outward or away from the blank or 110 piece of stock on the centers. 115 120

During the practical operation of the machine, it will be understood that all the operator has to do is to place blanks on and remove turned articles from the supports v and v', and that by manipulating the lever W'', the operator is enabled to quickly stop all of the parts that derive motion from the shaft O, and in that way prevent damage to said parts in the event of accident. It will also 125 130

be understood that the blanks are placed one by one on the supports v and v' and on center W by the hand of the operator while the parts are in the position shown in Fig. 5; the **V** shape of the supports serving to guide the blank to center, and as the shaft O continues to rotate the cam s thereon serves through the mechanism described to throw the tail-stock spindle D' inward with the result that one end of the blank will be forced upon the live center W' and caused to turn therewith, and at the same time the support v' will be drawn down away from the blank. During the "knocking on" described, the carriage F is held by spring C^3 against the stop b , and when the blank begins to turn freely on the centers, the cam p on shaft O engages roller r on lever K and through the connection described moves the carriage F toward the right in Fig. 2 to enable the tools 9 and 10 to do the rough cutting and shape the blank. Then when the cam p passes out of engagement with the roller r , the carriage F is returned by the means described to its position against the stop b . The movements of the parts are so timed that immediately after the movement of the carriage F toward the right, *i. e.*, in the direction of the arrow in Fig. 2 of the drawings is completed, the cam u on shaft O will engage the roller z'' of lever K' , and said lever will be rocked so as to move the carriage L inward and the finishing tool or tools thereon into contact with the blank. On disengagement of the cam u from roller z'' and during or immediately after the outward movement of the carriage L , the cam s' on shaft O engages the roller z' on the lever P' to throw the tail-stock spindle D' outward, when the center W of said spindle will be disengaged from the finished article, and at the same time said article will be displaced from the center W' by the means described and caused to drop in the supports v and v' .

The operation described requires approximately six seconds, and as the operator has nothing else to do he can remove the turned articles from the supports v v' with one hand and place blanks on the supports with his other hand, and thus keep up with the speed of the machine.

When articles other than bobbins are to be turned, it is obvious that various tools may be substituted for those herein shown and described.

The construction herein shown and described constitutes the preferred embodiment of my invention, but it is obvious that in the future practice of the invention such changes or modifications may be made as fairly fall within the scope of the invention as defined in the claims appended.

Having described my invention, what I claim and desire to secure by Letters-Patent is:

65 1. The combination in a turning machine,

of spindles one of which is movable longitudinally toward and from the other, a vertically movable stock support arranged adjacent to the other spindle and connected and movable with the longitudinally movable spindle, 70 means for depressing said support on inward movement of the longitudinally movable spindle, means for raising the support on outward movement of the said spindle, and a displacing device connected and movable 75 with the longitudinally movable spindle and arranged adjacent and movable with respect to the other spindle.

2. The combination in a turning machine, of a live spindle, a spindle movable endwise 80 toward and from the live spindle, a stock support arranged adjacent to the endwise movable spindle, a fixed bar extending in the direction of movement of said spindle and having an inclined shoulder on its lower edge, 85 a vertically movable stock support arranged adjacent to the live spindle and connected with the endwise movable spindle and having a portion arranged to be moved against the said inclined shoulder of the bar to effect 90 downward movement of the support on inward movement of the endwise movable spindle, a spring for raising the support on outward movement of said spindle when the said portion of the support shall have moved 95 outward beyond the said inclined shoulder of the fixed bar, and an upright connected and movable with the endwise movable spindle and having a portion loosely receiving the live spindle. 100

3. The combination in a turning machine, of spindles, one of which is movable endwise toward and from the other, a carriage movable in the direction of the length of the spindles, a second carriage movable at an angle 105 to the direction of movement of the first mentioned carriage, cutting tools on the carriages, means for moving the endwise movable spindle inward, moving the carriages, and moving the endwise movable spindle outward, in the order named, a stock support arranged adjacent to the endwise movable spindle, a vertically movable stock support connected and movable with said spindle and arranged adjacent to the other spindle, means for depressing the latter support on inward movement of the endwise movable spindle, and means for raising said support to its normal position on outward movement of the endwise movable spindle. 115

4. The combination in a turning machine, of a live spindle, a spindle movable endwise toward and from the live spindle, a carriage movable in the direction of the length of the spindles, a second carriage movable at an angle 125 to the direction of movement of the first mentioned carriage, cutting tools on the carriages, means for moving the endwise movable spindle inward, moving the carriages, and moving the endwise movable 130

- spindle outward, in the order named, a stock support arranged adjacent to the endwise movable spindle, a vertically movable stock support connected and movable with said spindle and arranged adjacent to the live spindle, means for depressing the latter support on inward movement of the endwise movable spindle, and means for raising said support to its normal position on outward movement of the endwise movable spindle. 10
5. The combination in a turning machine, of spindles, one of which is movable endwise toward and from the other, a carriage movable in the direction of the length of the spindles, a second carriage movable at an angle to the direction of movement of the first mentioned carriage, cutting tools carried by the carriages, means for moving the endwise movable spindle inward, moving the carriages, and moving the endwise movable spindle outward, in the order named, a vertically movable stock support connected and movable with the endwise movable spindle and arranged adjacent to the spindle opposed to the endwise movable spindle, means for depressing the said support on inward movement of the endwise movable spindle, and means for raising said support to its normal position on outward movement of the endwise movable spindle. 20
30. 6. The combination in a turning machine, of a live spindle, a spindle movable endwise toward and from the live spindle, a carriage movable in the direction of the length of the spindles, a second carriage movable at an angle to the direction of movement of the first mentioned carriage, cutting tools carried by the carriages, means for moving the endwise movable spindle inward, moving the carriages, and moving the endwise movable spindle outward, in the order named, a vertically movable stock support connected and movable with the endwise movable spindle and arranged adjacent to the live spindle, 35 means for depressing the said support on inward movement of the endwise movable spindle, and means for raising said support to its normal position on outward movement of the endwise movable spindle. 40
45. 7. The combination in a turning machine, of a frame, a transverse shaft, four cams fixed thereon, a longitudinally-disposed, endwise movable spindle, upright levers fulcrumed at intermediate points of their length 50 in the frame and having their upper arms connected with said spindle and their lower arms arranged to be engaged by two of the said cams, a carriage movable in the direction of the length of the spindle, a cutting tool carried by the carriage, a vertically swinging lever having an arm connected with the carriage to move the latter in one direction and also having an arm arranged to be engaged by a third cam of the transverse shaft, a second carriage movable at an angle 60

to the first mentioned carriage, a cutting tool carried by the second mentioned carriage, and a vertically swinging lever having an arm connected with the second mentioned carriage to move said carriage in one direction and also having an arm arranged to be engaged by the fourth cam on the transverse shaft; the latter arm being weighted to move the carriage in the opposite direction. 70

8. The combination in a turning machine, of spindles, one of which is movable longitudinally toward and from the other, a stock support connected and movable longitudinally with said spindle and also movable vertically and arranged adjacent to the spindle opposed to the longitudinally movable spindle, means for depressing said stock support on inward movement of the longitudinally movable spindle, and means for raising said stock support on outward movement of the longitudinally movable spindle. 75

9. The combination in a turning machine, of a longitudinally movable spindle, a vertically movable stock support connected and movable with the longitudinally movable spindle, means for depressing said support on inward movement of the spindle, and means for raising the support on outward movement of the spindle. 90

10. The combination in a turning machine, of a longitudinally movable spindle, a fixed bar extending in the direction of movement of said spindle and having an inclined shoulder on its lower edge, a vertically movable stock support connected with the spindle and having a portion arranged to be moved against the said inclined shoulder of the bar to effect downward movement of the support on inward movement of the spindle, and a spring for raising the support on outward movement of the spindle when the said portion of the support has moved outward beyond the said inclined shoulder of the fixed bar. 95

11. The combination in a turning machine, of a live spindle, a spindle movable endwise toward and from the live spindle, a stock support arranged adjacent to the endwise movable spindle, a fixed bar extending in the direction of movement of said spindle and having an inclined shoulder on its lower edge, a vertically movable stock support arranged adjacent to the live spindle and connected with the endwise movable spindle and having a portion arranged to be moved against the said inclined shoulder of the bar to effect downward movement of the support on inward movement of the endwise movable spindle, and a spring for raising the support on outward movement of said spindle when the said portion of the support shall have moved outward beyond the said inclined shoulder of the fixed bar. 110

12. The combination in a turning machine, of a live spindle, a spindle movable endwise 115

1 toward and from the live spindle, a fixed bar
2 extending in the direction of the length of the
3 spindles and arranged under the live spindle
4 and having an inclined shoulder at its lower
5 edge, a longitudinal rod connected through a
6 hanger with the endwise movable spindle and
7 movable endwise with said spindle, a vertically
8 movable stock support connected with
9 said rod and arranged adjacent to the live
10 spindle and having a portion movable against
11 the shoulder of the fixed bar to depress the
12 support on inward movement of the spindle,
13 and a spring for raising the support when the
14 said portion thereof shall have passed the
15 said inclined shoulder on outward movement
16 of the endwise movable spindle.

13. The combination in a turning machine,
14 of a live spindle, a spindle movable endwise
15 toward and from the live spindle, a fixed bar
16 extending in the direction of the length of the
17 spindles and arranged below and adjacent to
18 the live spindle and having an inclined shoul-
19 der at its lower edge, a longitudinal rod connected
20 through a hanger with the endwise
21 movable spindle and movable endwise with
22 said spindle, a vertically movable stock sup-
23 port connected with said rod and arranged
24 adjacent to the live spindle and having a portion
25 movable against the shoulder of the
26 fixed bar to depress the support on inward
27 movement of the endwise movable spindle, a
28 spring for raising the support when the said
29 portion thereof shall have passed the said in-
30 clined shoulder on outward movement of the
31 endwise movable spindle, and an upright
32 connected and movable with the said rod
33 and having a portion loosely receiving the
34 live spindle.

14. The combination in a turning machine,

of a stationary stock support, spindles one of 40
which is movable longitudinally toward and
from the other; the said longitudinally mov-
able spindle being arranged on its inward
movement to displace stock from the sta-
tionary support, a vertically movable stock 45
support arranged adjacent to the other spin-
dle and connected and movable with the lon-
gitudinally movable spindle, means for de-
pressing said support on inward movement
of the longitudinally movable spindle, and 50
means for raising the support on outward
movement of the said spindle.

15. The combination in a turning machine,
of a stationary stock support, spindles one of
which is movable longitudinally toward and 55
from the other; the said longitudinally mov-
able spindle being arranged on its inward
movement to displace stock from the sta-
tionary support, a vertically movable stock
support arranged adjacent to the other spin- 60
dle and connected and movable with the lon-
gitudinally movable spindle, means for de-
pressing said support on inward movement
of the longitudinally movable spindle, means
for raising said support on outward move- 65
ment of said spindle, and a displacing device
connected and movable with the longitudi-
nally movable spindle and arranged adjacent
and movable with respect to the other spin-
dle. 70

In testimony whereof I have hereunto set
my hand in presence of two subscribing wit-
nesses.

JAMES YOUNG.
